(57) **CLAIM**

The ornamental design for a wrench handle, as shown and described.

DESCRIPTION

FIG. 1 is a view in perspective of a wrench handle. FIG. 2 is a front plan view of the wrench handle of FIG. 1. FIG. 3 is a back plan view of the wrench handle of FIG. 1. FIG. 4 is a top view of the wrench handle of FIG. 1. FIG. 5 is a bottom view of the wrench handle of FIG. 1. FIG. 6 is an end plan view of the wrench handle of FIG. 1; and, FIG. 7 is an end view of the wrench handle of FIG. 1. The broken line showing of the tool ends of the wrench is for illustrative purposes only and forms no part of the claimed design.
